UNITED STATES PATENT OFFICE.

THOMAS HEATH, OF ATTLEBORO, MASSACHUSETTS, ASSIGNOR TO THE STANDARD BUTTON COMPANY, OF ATTLEBORO, MASSACHUSETTS.

DESIGN FOR A PIN OR SIMILAR ARTICLE.

55,042.

Specification for Design.

Patented May 4, 1920.

Application filed February 13, 1918. Serial No. 216,970. Term of patent 3½ years.

To all whom it may concern:

Be it known that I, THOMAS HEATH, a subject of King George of England, residing in the city of Attleboro, county of Bristol, and Commonwealth of Massachusetts, have invented a new, original, and ornamental Design for a Pin or Similar Article, of which the following is a specification, reference being had to the accompanying drawing, forming a part thereof.

The figure is a view in elevation of a pin or similar article illustrating my design.

I claim:

The ornamental design for a pin or similar article as shown.

THOMAS HEATH.
